W. H. GILBERT

WATER POWER INTAKE

Filed May 29, 1924

FIG. 1.

FIG. 2.

FIG. 3.

INVENTOR,
William Hall Gilbert
By Martin Smith, Atty.

UNITED STATES PATENT OFFICE.

WILLIAM HALL GILBERT, OF LOS ANGELES, CALIFORNIA.

WATER-POWER INTAKE.

Application filed May 29, 1924. Serial No. 716,584.

My invention relates generally to power production appliances, and more particularly to an intake in the nature of a duct or flume, by means of which the potential force and power of water, as found in swift running streams, is converted into hydraulic energy and used in the operation of a turbine or like rotor.

The principal objects of my invention are to provide a water power intake that is relatively simple in structure, capable of being easily and cheaply produced and installed and which requires practically no attention after having been placed in position for use.

Further objects of my invention are to construct the intake so that the main body portion thereof, that is positioned within the water has the desired degree of buoyancy and, further, to provide the intake with simple and efficient means for causing it to maintain a steady position within the stream.

With the foregoing and other objects in view, my invention consists in certain novel features of construction and arrangement of parts that will be hereinafter more fully described and claimed and illustrated in the accompanying drawings in which—

Fig. 1 is a top plan view of a water power intake of my improved construction.

Fig. 2 is a vertical longitudinal section taken on the line 2—2 of Fig. 1.

Fig. 3 is an enlarged cross section taken on the line 3—3 of Fig. 1.

Referring by numerals to the accompanying drawings which illustrate a practical embodiment of my invention, 10 designates a tubular body, preferably formed of suitable sheet metal, of any desired diameter and length and the outer end of this tubular body or the end that is positioned in the running water is flared outwardly so as to provide a funnel-shaped mouth 11.

In order to prevent drift wood and like foreign objects from entering the tubular body, the opening into the flaring mouth 11 may be provided with a screen 12 of suitable mesh.

To give that portion of the body of the intake, that projects outwardly into the running water, the necessary buoyancy, an air chamber 13, of suitable size is formed on

the underside of body 10 and tapered outer end 11.

To assist the body 10 in maintaining a steady position in the water, horizontally disposed, longitudinally extending fins or vanes 14 are secured to the sides of said body and its flaring end 11.

The body 10 of the intake, when positioned for use, occupies an angular position in a substantially horizontal plane adjacent to a wall of concrete or masonry W that is built at or near the bank of the stream, and is arranged substantially parallel therewith.

The intake is anchored to the wall W in any suitable manner, preferably by means of chains or cables 15, that are connected to said intake at suitable points and which extend to rings or posts 16 that are seated in said wall.

The inner end of the body 10 of the intake extends into a tubular member 17 that extends through and occupies an inclined position in a horizontal plane in wall W.

The fit or bearing of the end of intake 10 in tubular member 17, is such, that said intake, under certain stresses, may slide or rotate within said member 17.

Tubular member 17 is directly connected to a turbine or water wheel (not shown) and suitably located in said member is a gate valve 18 that may be manipulated to control the flow of water through the intake and to the turbine.

As illustrated in Figs. 1 and 2, the intake occupies a practically horizontal plane and projects from the wall W up stream and outwardly toward the center thereof.

When the intake is positioned in a suitably running stream and the valve 18 is opened, a practically constant volume of water flows into and through said intake and the hydraulic force and power of this confined volume flow is delivered to the turbine to operate same and produce mechanical energy that may be utilized as desired.

Obviously, a plurality of the intakes may be arranged adjacent to a wall, thereby producing, at one station or plant, a relatively large amount of power.

To prevent floating objects, such as logs and large pieces of ice from striking the flaring screened end of the intake, an inclined deflector plate may be suitably an-

chored or positioned in the stream a short distance in front of said screened end.

A water power intake of my improved construction is relatively simple, requires practically no attention after installation and is very effective in performing its intended functions.

It will be understood that minor changes in the size, form and construction of the various parts of my improved water power intake may be made and substituted for those herein described without departing from the spirit of the invention, the scope of which is set forth in the appended claims.

15 I claim as my invention:

1. A water power intake comprising a tubular member having a flaring mouth at one end, means for anchoring said tubular member in a flowing stream at an angle relative to the direction of flow of water in said stream and there being an air chamber formed on the underside of said tubular

member and extending substantially the entire length thereof for rendering the same buoyant.

2. The combination with a wall arranged adjacent to a flowing stream, of a tubular member extending through said wall and projecting a substantial distance outwardly therefrom into the stream at an angle relative to the line of flow thereof there being an air chamber formed on the underside of said tubular member and extending substantially the entire length thereof for rendering said tubular member buoyant, stabilizing means arranged longitudinally on the sides of said tubular member, the intake of said tubular member having a flaring mouth, and means for controlling the flow of water through said tubular member.

30 In testimony whereof I affix my signature.

40 WILLIAM HALL GILBERT.
